THERAPY TABLE TOP

Warren S. Radford, 29325 Edgedale Road,
Pepper Pike, Ohio 44124

Filed Apr. 3, 1972, Ser. No. 240,897

Term of patent 14 years

Int. Cl. D24—01

U.S. Cl. D83—1 D

FIG.1

FIG. 1 is a perspective view of a therapy table top showing my new design;

FIG. 2 is a side view of a therapy table top shown in FIG. 1 with the opposite side being a mirror image thereof;

FIG. 3 is a top plan view thereof;

FIG. 4 is an end view looking from the right-hand side of FIG. 2 thereof; and

FIG. 5 is an end view looking from the left-hand side of FIG. 2 thereof.

The broken lines are shown for illustrative purposes only.

I claim:

The ornamental design for a therapy table top, as shown and described.
